DISCHARGE HEAD FOR PRESSURE
FLUID TANKS

Frederick A. Dodelin, Glen Ridge, N. J., assignor
to Pyrene Manufacturing Company, Newark,
N. J., a corporation of Delaware

Application October 10, 1946, Serial No. 702,549

15 Claims. (Cl. 222—5)

1

This invention relates to a head or unit adapted to be applied to a sealed discharge opening or fitting of a tank containing a fluid under pressure. More particularly, it relates to a unit of this character having an explosively operated member arranged to shear or break or otherwise provide an opening through the sealing disc or other means which normally closes the discharge opening of such a tank.

A primary object of the invention has been to provide a discharge head of the character indicated which is of simple construction, easy to use, and reliable in its operation.

Another object has been to provide an explosion chamber in such a unit that requires a minimum of attention in the use of the device. Heretofore, devices of this sort have required careful cleaning after each use to insure their proper operation during a succeeding use. Considerable time and effort has been required in conditioning the device for reuse on a new tank or on the same tank after it has been recharged.

Difficulties have also been encountered in the past due to overheating of certain parts upon the explosion of the operating charge so that the parts have been damaged or have failed to function properly either during the same or a subsequent operation. A further object of the invention has, therefore, been to eliminate as far as possible the danger of overheating.

Other objects, features, and advantages of the invention will appear from a detailed description of an illustrative embodiment of the invention which will now be given in conjunction with the accompanying drawing in which the single figure is a longitudinal sectional view through the unit.

While the invention may be advantageously utilized in connection with systems of various sorts in which there is a need for a relatively quick discharge of a fluid from a pressure tank, it is particularly adapted for use in fire extinguisher systems of the type installed on airplanes and the like. As set forth in the application of Frederick A. Dodelin and Peter G. MacGregor, Serial No. 562,300, filed on November 7, 1944, now Patent No. 2,419,826, April 29, 1947, a discharge head of the type contemplated may be arranged to control the delivery of a fire extinguishing fluid, such as methyl bromide, carbon tetrachloride, carbon dioxide, or the like, provided in a tank under a pressure of, say, around 150 lbs. per sq. in. When a fire breaks out in one of the engines, or some other vulnerable point, the pilot closes a switch which sets off an explosive charge in the discharge head and the fire extinguishing

2

fluid is then delivered under pressure from a tank to a series of jets or nozzles disposed at strategic points. The arrangement is usually such that the contents of the tank is substantially fully discharged within a few seconds with the result that combustion can no longer be supported in the regions covered by the various jets.

Referring now to the drawing, a fitting 10 is shown, this being adapted for attachment in any suitable way to a tank containing a fluid under pressure. If desired, the fitting may simply extend through an opening in the tank and may then have its laterally extending flange 11 secured in any suitable way, as by welding, to the outer surface of the tank wall. If the tank is already provided with a discharge fitting which is internally threaded, external threads 12 on the fitting 10 may be used to retain the latter and this may, if desired, be supplemented by welding or the like. In the event that the tank has a discharge fitting in the form of an externally threaded neck, internal threads 13 on the fitting 10, either alone or in conjunction with welding or the like, may be employed for the attachment of the latter. In whatever way the fitting is attached, provision should be made for effective sealing around the fitting as by the use of washers, gaskets, or the like.

The fitting 10 is provided with an axially extending neck 14 having internal threads 15 adapted to receive a clamping element 16 for retaining a sealing disc 17 against a shoulder 18 which extends inwardly at the bottom of the neck 14. An annular depression 19 is preferably provided around the shoulder 18 and this may, if desired, cooperate with a corresponding bead (not shown) on the under surface of the retainer 16. Sealing disc 17 may be formed of any of the usual materials, such as copper, a suitable plastic, or the like, and when clamped in place is adapted to provide a protective seal capable of resisting the pressure of the fluid in the tank. If desired, the seal and the retaining means may be of the character disclosed in said Dodelin-MacGregor application, Serial No. 562,300.

The neck 14 is also threaded externally, as indicated at 20, to receive internal threads on an enlarged portion 21 of a main housing 22. A gasket 21a of suitable material is squeezed between the upper end of neck 14 and a shoulder of the housing to provide a seal at this point. This housing is hollow and provides three separate connected chambers 23, 24, and 25 of successively larger diameter. Within the chamber 23 there is slidably mounted a hollow cutter mem-

ber 26 of generally cylindrical form having an annular cutting edge 27 at its lower end which is inclined slightly to a plane normal to the axis of the unit. The cutter 26 is also provided with a central pin or spike 28 having a sharp point and adapted to pierce the sealing disc at its center. As the cutter 26 is shifted axially, in the manner to be explained, the pin 28 first pierces the sealing disc 17 and the shearing edge 27 then shears off the disc at the inner edge of the shoulder 18. To prevent rotation of the cutter 26, as it slides within the chamber 23, a pin 29 is provided through the wall of the housing. This cooperates with an elongated slot 30 in the wall of the cutter 26.

A piston member 31 having a laterally extending flange 32 at its upper end is slideable within the chambers 24 and 25 of the housing. The main body of the piston is adapted to fit the bore of the chamber 24, while the flange 32 is arranged to slide along the wall of the chamber 25. A spring 33, which surrounds the piston within the chamber 25, acts at its upper end against the flange 32 and at its lower end against a shoulder 34 of the housing. This spring tends to keep the piston in its upper position as shown in the drawing. A flat annular plate 35 is provided across the upper end of the housing member 22 and is arranged to be clamped against the latter by a cup-like member 36 which forms another part of the housing. As shown, the member 36 is provided with internal threads adapted to engage external threads at the upper end of member 22. An inwardly extending shoulder within the member 36 serves to clamp the disc 35 and provides a chamber 37 which may be considered a part of the explosion chamber. The latter is also formed in part by successively reduced portions 38 and 39 of the space within member 36.

At its upper or outer end the member 36 is externally threaded to receive internal threads on a cap 40 which serves to retain a plug 41 within the upper end of member 36 and squeezes this plug against a gasket or washer 42 which provides an effective seal at the upper end of the explosion chamber. Plug 41 is preferably formed of hard rubber or some suitable plastic material having good dielectric properties and capable of withstanding the heat and pressure of the explosion to which the device is subjected. A downwardly extending central portion 43 of the plug is adapted to frictionally receive the upper open end 44 of a suitable small cartridge. The latter contains a charge of gun powder or other suitable explosive 45 which is held in the shell by a paper wad or disc 46. Plug 41 has a further downward extension 47 which is embedded in the powder charge 45. A pair of long passages 48, extending through the plug 41 from its outer to its inner end, serves to receive and retain the two legs of a U-shaped electrical resistance wire 49, the opposite ends of which are connected to binding posts 50. As will be understood, when it is desired to discharge the contents of the tank to which the unit is attached, current from a suitable source will be passed through the wire 49 to ignite or set-off the charge 45. For the purpose of sealing off the upper ends of the passages 48, a small disc or washer 51 is provided, this being held in place by a screw 52. The disc 51 may suitably be formed of rubber or other insulating material capable of providing a good seal.

Within the piston 31 is provided a centrally disposed member 53 which is largely hollow to

provide a recess, as indicated at 54, at its upper end. This recess forms an extension of the explosion chamber within the piston. At its upper end the member 53 is provided with a laterally extending flange 55 which is normally held substantially in engagement with a shoulder on the member 36. If desired the engagement of flange 55 with said shoulder may determine the upper limit of movement of the piston and a slight clearance may be provided between flange 32 and the plate 35. In the operation of the device the flange 55 shifts freely within the chamber 37. Member 53, piston 31, and cutter 26 are preferably held together as a unitary assembly by means of a screw-threaded portion 56 at the upper end of the spike 28. This screw-threaded portion of the spike engages threads within the member 53 so that the spike serves to clamp all of the parts together.

An annular space is provided within the piston 31 around the member 53. Within this space a Sylphon bellows 57, formed preferably of copper or bronze, or stainless steel, is provided, this having its upper end attached by welding, soldering, or the like to the under surface of the inner edge of the annular plate 35. The other end of the Sylphon bellows is preferably clamped between the lower end of the member 53 and the bottom of the piston, in the manner shown. If desired, any other or additional means, such as soldering, welding, or the like, may be employed to retain the lower end of the bellows.

It will be apparent that as explosive charge 45 is ignited, in the manner explained, by the passage of an electrical current through the wire 49, the gasses developed by the explosion will force the piston 31 and all of the connected parts downwardly to puncture and shear the sealing disc 17 and thus allow the fluid within the tank to flow upwardly through the interior of the cutter 26, outwardly through an opening in the side wall of the cutter, and into a laterally extending outlet branch 58. The latter may be threaded, as shown at 59, to receive any suitable form of coupling to connect the housing with a hose line or tubing for the delivery of the fluid to the desired points of use.

The smoke and dirt generated upon the explosion of the charge 45 is retained within the explosion chamber and is definitely prevented from reaching the relatively sliding surfaces of the piston 31 and the housing 22 by means of the Sylphon bellows 57. This bellows also prevents overheating of the piston by preventing the transfer of heat, by convection, from the explosion gases directly to the inner wall of the piston. Moreover, most of the smoke and dirt generated upon the explosion will be confined to the pocket or chamber 54 within member 53 and the portions 38 and 39 of the main explosion chamber above the laterally extending flange 55. Of course, as the piston moves downwardly these gases will expand and follow the flange 55 downwardly. A small portion of the gases may pass around the outer edge of the flange 55 and may enter the pocket provided within the bellows. However, the relatively small amount of the gases which will do this will carry very little dirt or heat into the bellows 57 so that the latter is quite effectively shielded. The small amount of dirt which will lodge on the surfaces of the chamber 37 will not interfere seriously with the subsequent use of the device, because of the relatively loose fit of the flange 55 within this chamber. Therefore, it is not necessary to take the device apart and clean

it after each use. It may, however, be desirable to remove the member 36 and clean the parts within this after a number of uses of the device.

After the force of the explosion has been dissipated, the spring 33 will serve to restore the piston and the various connected parts to the position shown in the drawing and in doing so will move the member 53 with its flange 55 upwardly to expel the explosion gases through a vent hole 68 provided through the wall of the member 36. This vent hole, it will be understood, is relatively small so that it will not interfere with the delivery of the force of the explosion to the piston, but at the same time it allows for the escape of the gases after the work has been done.

While an illustrative form of the invention has been described in considerable detail, it will be understood that various changes may be made in the construction and arrangement of the various parts of the device without departing from the general principles and scope of the invention.

What I claim is:

1. A discharge head for a tank containing a fluid under pressure which comprises a main housing adapted to be applied to the discharge orifice of the tank, a reciprocable member slidably mounted within said housing and adapted upon movement to open a seal for said orifice, an enclosed explosion chamber within said housing, means for retaining an explosive charge within said chamber, means for causing explosion of said charge, said member having a surface against which the gases resulting from said explosion react to move said member within said housing to open said seal, and an elongatable protecting member held at one end by said housing and connected at its other end to said reciprocable member arranged to prevent access of said gases to the relatively sliding surfaces of said reciprocating member and housing.

2. A discharge head for a tank containing a fluid under pressure which comprises a main housing adapted to be applied to the discharge orifice of the tank, a reciprocable member slidably mounted within said housing and adapted upon movement to open a seal for said orifice, an enclosed explosion chamber within said housing, means for retaining an explosive charge within said chamber, means for causing explosion of said charge, said member having a surface against which the gases resulting from said explosion react to move said member within said housing to open said seal, and a Sylphon bellows member held at one end by said housing and connected at its other end to said reciprocable member arranged to prevent access of said gases to the relatively sliding surfaces of said reciprocating member and housing.

3. A discharge head for a tank containing a fluid under pressure which comprises a main housing adapted to be applied to the discharge orifice of the tank, a reciprocable member slidably mounted within said housing and adapted upon movement to open a seal for said orifice, an enclosed explosion chamber within said housing, means for retaining an explosive charge within said chamber, means for causing explosion of said charge, said member having a surface against which the gases resulting from said explosion react to move said member within said housing to open said seal, an elongatable protecting member held at one end by said housing and connected at its other end to said reciprocable member arranged to prevent access of said gases to the relatively sliding surfaces of said reciprocating

member and housing, and means carried by said reciprocating member positioned between said protecting member and said explosive charge to substantially prevent direct contact of said gases with said protecting member.

4. A discharge head for a tank containing a fluid under pressure which comprises a main housing adapted to be applied to the discharge orifice of the tank, a reciprocable member slidably mounted within said housing and adapted upon movement to open a seal for said orifice, spring means for urging said member in one direction, an enclosed explosion chamber within said housing, means for retaining an explosive charge within said chamber, means for causing explosion of said charge, said member having a surface against which the gases resulting from said explosion react to move said member within said housing against the action of said spring means to open said seal, and an elongatable protecting member held at one end by said housing and connected at its other end to said reciprocable member arranged to prevent access of said gases to the relatively sliding surfaces of said reciprocating member and housing.

5. A discharge head for a tank containing a fluid under pressure which comprises a main housing adapted to be applied to the discharge orifice of the tank, a reciprocable member slidably mounted within said housing and adapted upon movement to open a seal for said orifice, spring means for urging said member in one direction, a shoulder carried by said housing providing a stop against which said member is normally held by said spring means, an enclosed explosion chamber within said housing, means for retaining an explosive charge within said chamber, means for causing explosion of said charge, said member having a surface against which the gases resulting from said explosion react to move said member within said housing against the action of said spring means to open said seal, and an elongatable protecting member held at one end by said housing and connected at its other end to said reciprocable member arranged to prevent access of said gases to the relatively sliding surfaces of said reciprocating member and housing and to said shoulder.

6. A discharge head for a tank containing a fluid under pressure and having a sealed discharge orifice which comprises a housing associated with said orifice, a piston member reciprocable in said housing to destroy the seal for said orifice, said housing having an explosion chamber at one end of said member, an explosive charge within said chamber, means for igniting said charge to cause operation of said piston member, spring means for restoring said piston member, and an elongatable sleeve member connected at one end with said housing and at its other end with said piston member for shielding the cooperating surfaces of said piston and housing against the gases resulting from explosion of said charge.

7. A discharge head for a tank containing a fluid under pressure and having a sealed discharge orifice which comprises a housing associated with said orifice, a piston member reciprocable in said housing to destroy the seal for said orifice, said housing having an explosion chamber at one end of said member, an explosive charge within said chamber, means for igniting said charge to cause operation of said piston member, spring means for restoring said piston member, venting means for permitting the relatively

slow escape of gases from said explosion chamber, and an elongatable sleeve member connected at one end with said housing and at its other end with said piston member for shielding the cooperating surfaces of said piston and housing against the gases resulting from explosion of said charge.

8. A discharge head for a tank containing fluid under pressure and having a sealed discharge orifice, said head comprising a main hollow housing having an inwardly extending wall dividing the same into a piston receiving cylinder and an explosion chamber, a hollow piston slidable within said cylinder, spring means normally urging said piston against said wall, explosive means carried by said housing within said chamber, means for igniting said explosive means, said wall having an opening therein permitting access of the gases of explosion to said piston for propelling the same against the action of said spring means, means carried by said piston adapted to open said sealed orifice upon movement of the piston by the explosion gases, and means extending from said wall into the interior of said piston adapted to prevent access of said explosion gases to the relatively sliding surfaces of said piston and housing.

9. A discharge head for a tank containing fluid under pressure and having a sealed discharge orifice, said head comprising a main hollow housing having an inwardly extending wall dividing the same into a piston receiving cylinder and an explosion chamber, a hollow piston slidable within said cylinder, spring means normally urging said piston against said wall, explosive means carried by said housing within said chamber, means for igniting said explosive means, said wall having an opening therein permitting access of the gases of explosion to said piston for propelling the same against the action of said spring means, means carried by said piston adapted to open said sealed orifice upon movement of the piston by the explosion gases, and a Sylphon bellows connected at one end to said wall and at its other end to an interior portion of said piston adapted to prevent access of said explosion gases to the relatively sliding surfaces of said piston and housing.

10. A discharge head for a tank containing fluid under pressure and having a sealed discharge orifice, said head comprising a main hollow housing having an inwardly extending wall dividing the same into a piston receiving cylinder and an explosion chamber, a hollow piston slidable within said cylinder, spring means normally urging said piston against said wall, explosive means carried by said housing within said chamber, means for igniting said explosive means, said wall having an opening therein permitting access of the gases of explosion to said piston for propelling the same against the action of said spring means, means carried by said piston adapted to open said sealed orifice upon movement of the piston by the explosion gases, a Sylphon bellows connected at one end to said wall and at its other end to an interior portion of said piston adapted to prevent access of said explosion gases to the relatively sliding surfaces of said piston and housing, and means carried by said piston for shielding said bellows against the heat of the explosion gases.

11. A discharge head for a tank containing fluid under pressure and having a sealed discharge orifice, said head comprising a main hollow housing having an inwardly extending wall dividing the same into a piston receiving cylinder and an explosion chamber, a hollow piston slid-

able within said cylinder, spring means normally urging said piston against said wall, explosive means carried by said housing within said chamber, means for igniting said explosive means, said wall having an opening therein permitting access of the gases of explosion to said piston for propelling the same against the action of said spring means, means carried by said piston adapted to open said sealed orifice upon movement of the piston by the explosion gases, a Sylphon bellows connected at one end to said wall and at its other end to an interior portion of said piston adapted to prevent access of said explosion gases to the relatively sliding surfaces of said piston and housing, and means carried by said piston for shielding said bellows against the heat of the explosion gases, said last mentioned means comprising a radially extending flange within said explosion chamber extending substantially to the wall thereof.

12. A discharge head for a tank containing fluid under pressure and having a sealed discharge orifice, said head comprising a main hollow housing having an inwardly extending wall dividing the same into a piston receiving cylinder and an explosion chamber, a hollow piston slidable within said cylinder, spring means surrounding said piston and normally urging said piston against said wall, explosive means carried by said housing within said chamber, means for igniting said explosive means, said wall having an opening therein permitting access of the gases of explosion to said piston for propelling the same against the action of said spring means, means carried by said piston adapted to open said sealed orifice upon movement of the piston by the explosion gases, and means extending from said wall into the interior of said piston adapted to prevent access of said explosion gases to the relatively sliding surfaces of said piston and housing and to said spring means.

13. A discharge head for a tank containing fluid under pressure and having a sealed discharge orifice, said head comprising a main hollow housing formed in two separable but interconnected parts, a flat annular member between said parts serving to divide the interior of said housing into a piston receiving cylinder and an explosion chamber, a hollow piston slidable within said cylinder, spring means normally urging said piston against said member, explosive means carried by said housing within said chamber, means for igniting said explosive means, said member having an opening therein permitting access of the gases of explosion to said piston for propelling the same against the action of said spring means, means carried by said piston adapted to open said sealed orifice upon movement of the piston by the explosion gases, and means extending from said member into the interior of said piston adapted to prevent access of said explosion gases to the relatively sliding surfaces of said piston and housing.

14. A discharge head for a tank containing fluid under pressure and having a sealed discharge orifice, said head comprising a main hollow housing having an inwardly extending wall dividing the same into a piston receiving cylinder and an explosion chamber, a hollow piston slidable within said cylinder, spring means normally urging said piston against said wall, explosive means carried by said housing within said chamber, means for igniting said explosive means, said wall having an opening therein providing communication between said cylinder and chamber, said piston

having a cup-shaped portion and a seal opening portion, and a Sylphon bellows within said cup-shaped portion and having one end attached to the bottom thereof and the other end attached to said wall.

15. A discharge head for a tank containing fluid under pressure and having a sealed discharge orifice, said head comprising a main hollow housing having an inwardly extending wall dividing the same into a piston receiving cylinder and an explosion chamber, a hollow piston slidable within said cylinder, spring means normally urging said piston against said wall, explosive means car-

ried by said housing within said chamber, means for igniting said explosive means, said wall having an opening therein providing communication between said cylinder and chamber, said piston having a cup-shaped portion and a seal opening portion, a Sylphon bellows within said cup-shaped portion and having one end attached to the bottom thereof and the other end attached to said wall, and means carried by said piston within 5 said bellows for at least partially shielding the latter against the heat of the gases of explosion.

FREDERICK A. DODELIN.
